UNITED STATES PATENT OFFICE

JOHN LIPARI, OF HAWTHORNE, AND JOSEPH E. MATTHEWS, OF PATERSON, NEW JERSEY

OMBRE FABRIC

Application filed March 21, 1930. Serial No. 487,808.

This invention relates to an improved cloth, the object being to provide cloth of substantially any desired width having a single or double ombre effect.

Another object of the invention is to provide a piece of fabric wherein an ombre effect is secured by the way different shades of warp yarns are arranged, the shade tapering from one edge of the fabric to the other without a break, notwithstanding the fact that comparatively few distinct shades of yarn are used.

A further object of the invention is the provision of a piece of cloth presenting an ombre effect wherein the effect is secured by a limited number of colors through the grouping of the colors, and through the addition and dropping of certain colors in the groups from one side of the fabric to the other.

In the accompanying drawings—

Figure 1 is a plan view of a piece of cloth or fabric showing an ombre effect and disclosing an embodiment of the invention;

Figure 2 is a greatly enlarged fragmentary sectional view through Figures 1 and 3 on line 2—2 of both figures; and

Figure 3 is a diagram showing how the ombre effect in Figure 1 is secured in a piece of cloth twenty-four inches wide.

In weaving cloth heretofore it has been difficult to secure an ombre effect except in a very narrow piece of goods, because it is impossible to differentiate sufficiently in shades to have an independent shade for each warp yarn in an average piece of cloth. In a piece of silk cloth twenty-four inches wide usually there are 5,760 yarns or ends.

It would be physically impossible to make this number of shades of any color and, consequently, it has proven impossible heretofore to produce an ombre effect upon a piece of goods twenty-four inches wide, or even ten inches wide.

In the present invention a single ombre effect may be secured on a piece of cloth twenty-four inches wide, forty-eight inches wide, or any other desired width within reason. By providing what is known as a double ombre effect, which is merely a re-

verse arrangement of the yarns, double the width may be secured.

In the present invention a comparatively limited or restricted number of shades are used, and in the drawings 13 shades have been illustrated, although a greater or less number of shades may be used without departing from the spirit of the invention.

In providing the cloth shown in Figure 1, or cloth of any desired width, the weft yarns are preferably what is known as the middle color. Warp yarns are arranged in groups or sub-groups as hereinafter described to secure a gradual change in shade from one edge of the cloth to the other. Where 13 shades are used as illustrated in the accompanying drawings, the weft yarns would preferably be shade No. 7, although No. 6 or No. 8 might be used without changing the general effect. If a lighter or darker shade were used it would make the entire piece of cloth lighter or darker, but would not change the ombre effect.

In order that the invention may be clearly understood the groups of warp yarns have been shown in diagram in Figure 3. Referring particularly to this diagram it will be seen that the group 40, or "dial" as it is sometimes termed, consists of one shade and is repeated 32 times. By this it is understood that one edge of the cloth starts with the shade No. 1 of a given color and the first 32 yarns are of the same shade. Following the first group or "dial", which in the present specification will be known hereafter as a master group, other groups follow in certain order and repeated certain numbers of times.

It has been found desirable that following group 40 is a second group 41 which repeats 15 times. Group 41 is made up of two shades, namely shade No. 1 and shade No. 2. By repeating this group 15 times there will be presented 15 shades of No. 1 and 15 shades of No. 2 to make 30 yarns or "ends". Following master group 41 is a master group 42 which is repeated 10 times. Master group 42 is made up of three shades, namely shade No. 1, shade No. 2 and shade No. 3, and when this

group is repeated 10 times there will be 30 yarns or ends, ten of each shade.

Ordinarily in weaving a twenty-four inch piece of silk goods a No. 60 reed is used and 5 four yarns are placed in each dent. This will produce one inch of cloth for each 240 yarns or ends. By carrying the same method throughout the entire reed, 5,760 yards or ends will be necessary to produce a twenty- 10 four inch piece of cloth. Where the yarns are larger, that is greater in diameter, than the silk a less number of ends may be used. In cotton or woolen goods the yarns are thicker and, consequently, an appreciably less 15 number of ends will be used, but the same grouping as shown in Figure 3 will be followed.

Referring again to Figure 3 it will be seen that the master group 43 follows group 42 20 and contains 1 sub-group 44. Each sub-group 44 has four shades in the master group 43, while the sub-group 44 in the master group 42 has only three shades. By having four shades in each sub-group of master 25 group 43 there will be 17 yarns of each shade in this group and, consequently, a total of 68 ends in group 43.

In the master group 45 there are three sub-groups 44 and as master group 45 is repeated 17 times 204 yarns will be used in this group. In groups 40 to 43 it will be noted that a new shade is added successively to the 30 respective groups until there are four shades in master group 43. In master group 45 it will be noted that the last sub-group 44 starts a new shade, namely, shade No. 5, and stops or drops shade No. 1. This will naturally produce a slight difference in color in that part of the cloth because there are 17 yarns 35 having the No. 5 shade. As this group will produce about one-eighth inch of cloth the change in shade in this short section would not be noticeable, but as this system progresses for the entire twenty-four inches the eye will 40 notice that the shade gradually changes from one side of the cloth to the other.

Master group 46 follows group 45 and contains two sub-groups 44, one sub-group having shades No. 1 to No. 4 and the other shades 45 No. 2 to No. 5, thus making a very narrow section as, for instance, one-sixteenth inch of cloth wherein there are 17 ends of the color No. 5. It will be noted that this causes an added change in shade of the cloth as the 50 shade No. 5 is greater in proportion to the remaining yarns than in the case of master group 45.

In master group 47 three sub-groups 44 are provided and two of these have shade No. 5 as one of the yarns so that there is only one group having the first four shades. As this master group is repeated 17 times there will be a greater predominance of shade No. 5 and shade No. 1 will be almost lost. In 55 fact, this is the last master group in which

shade No. 1 appears. It will thus be seen that shade No. 5 starts in master group 45 and shade No. 1 ends in master group 47. Master group 48 has no sub-groups and consists of shades No. 2 and No. 5 inclusive. This makes 60 more dominant shade No. 5. Following master group 48 is a master group 49 having three sub-groups 44 none of which have shade No. 1, but one of which has shade No. 6, as shade No. 6 starts in this group. 65

Master group 50 has two sub-groups 44, one having shades No. 2 to No. 5 inclusive, and the other having shades No. 3 to No. 6 inclusive, thus making shade No. 6 more dominant than it was in master group 49 and shade No. 2 less dominant. Master group 51 has three sub-groups 44, and in this master group shade No. 2 appears for the last time and shade No. 6 is found in two of the sub-groups. Master group 52 has three shades 80 No. 3 to No. 6 inclusive, thus completely eliminating shade No. 2 and making shade No. 6 more prominent.

Following group 52 are groups 53, 54, 55, 56, 57, 58, 59, 60, 61, 62, 63, 64, 65, 66, 67, 68, 69, 70, 71, 72, 73, 74, 75, 76, 77, 78, 79, 80, 81, 82 and 83. These groups follow the same order as just disclosed in regard to groups 40 to 52. It will be observed that at certain intervals a certain shade is dropped or disappears and a certain other shade appears or starts.

At the opposite side of the cloth to that designated by group 40 will be found group 83 which has the thirteenth shade, and it will be noted that group 83 is repeated 32 times in a similar manner to group 40, so that there will be 32 shades of No. 1 in group 40 and 32 yarns of shade No. 13 in group 83. Group 82 has two shades and group 81 three shades, and so on in the same order as described in respect to the opposite side of the cloth.

It will be noted that the different shades start at a certain point and disappear at a certain point. For instance, shade No. 6 is introduced as the 784th end or yarn. This yarn is present up to the 3755th end or a distance of 12 inches when the cloth is 24 inches wide. The lighter and heavier colors at the respective sides are not repeated quite so often and consequently appear in a less number of inches.

Thirteen shades have been set forth in the drawings, but if desired a greater or less number can be used. However, the grouping would be the same in principle as has been set forth and as shown particularly in Figure 3.

Regardless of the number of shades used a single shade would be used for the first group preferably, although not necessarily, and then preferably two shades would be used for the second group, and so on until preferably four shades have been used as a basis for the sub-groups. It is evident, how-

ever, that a greater or less number of shades can be used for each sub-group and not depart from the spirit of the invention.

The showing in the drawings and description sets forth an ombre effect for a piece of cloth which is sometimes known as a single ombre because the shade gradually changes from one side of the cloth to the other. If desired, the ombre effect could be reversed, 10 and after getting one width the result would be 48 inches of cloth with a double ombre, the lightest colors being in the center and the darker shades at the two edges, or the reverse.

What we claim is:

15 1. A cloth having warp yarns forming an ombre effect, said yarns being positioned in groups with the shades in adjacent groups overlapping, and with the shades in the respective groups varying from one side of the 20 cloth to the other.

25 2. A cloth presenting an ombre effect, comprising weft and warp yarns, the weft yarns being of one color while the warp yarns present a plurality of shades, there being a less number of shades than there are warp 30 yarns, said warp yarns being arranged in groups, each group except the first of each shade consisting of a plurality of yarns of different shades, the shades in the respective groups changing from one side of the cloth to the other with the shades of adjacent groups overlapping.

35 3. A colored fabric varying gradually in color from a deep shade at one edge to a light shade at the opposite edge, said fabric including a plurality of groups of yarns, adjacent groups having shades overlapping with the groups in the center part of the fabric having added shades in each alternate 40 group.

45 4. A colored fabric varying gradually in color from a deep shade at one edge to a light shade at the opposite edge, said fabric including a plurality of master groups, certain of said master groups having a plurality of shades, each alternate master group having sub-groups adding and dropping a shade so that a gradual overlapping of shades will be secured in order that the entire color from 50 one edge of the cloth to the other will be without a striped effect.

55 5. A colored fabric varying in color with an ombre effect, said fabric including warp yarns arranged in groups of different ensemble effect, each group being repeated a certain number of times, certain of said groups having sub-groups, each sub-group comprising a plurality of yarns of different colors.

60 6. A fabric having warp yarns of different shades of color, the said yarns being arranged in groups with certain yarns of any group overlapping adjacent groups at each side.

65 7. A fabric formed with groups of sub-groups of warp yarns of different shades of

color, each group being repeated a plurality of times, and each sub-group being repeated a plurality of times.

8. A colored fabric presenting an ombre effect including master groups and sub-groups of warp yarns, the yarns in each master group being different from the ensemble color of the yarns in adjacent master groups, while certain of the sub-groups in each master group have yarns of the same 75 ensemble color.

9. A colored fabric presenting an ombre effect, including a plurality of master groups, each master group being of one ensemble color, certain of the master groups having sub-groups of an ensemble color effect, the colors in said master groups gradually changing from a deep shade at one edge of the fabric to a light shade at the opposite edge 85 of the fabric.
